UNITED STATES PATENT OFFICE.

LOUIS A. STRAUBEL, OF GREEN BAY, WISCONSIN, ASSIGNOR TO STRAUBEL MACHINE COMPANY, OF GREEN BAY, WISCONSIN.

REWINDING MACHINE.

Application filed March 14, 1922. Serial No. 543,546.

To all whom it may concern:

Be it known that I, LOUIS A. STRAUBEL, a citizen of the United States, and resident of Green Bay, in the county of Brown and State of Wisconsin, have invented certain new and useful Improvements in Rewinding Machines; and I do hereby declare that the following is a full, clear, and exact description thereof.

10 The invention is in machines for slitting, perforating and rewinding paper of the type on which Patent No. 1154301 was issued to J. C. Fogarty, September 21, 1915.

15 Machines for rewinding mill rolls of paper into toilet rolls that are perforated to make sheets must be very sensitive on account of the perforations. For this reason, the coil spindles must revolve easily and the friction for driving them must have delicate adjustment to prevent breaking the paper in the perforations while it is being wound into rolls. Breakage greatly increases the cost of production.

20 The invention comprises, in addition to mechanism described in the above identified application, three pulleys having a belt running thereon, one of the pulleys serving to move the belt. Resilient means is applied to another of the pulleys to tighten the belt. 25 A frame carrying three pulleys adapted to frictionally engage one at a time with the belt and three core spindles adapted to be rotated by these pulleys, are provided. A pair of core frames are rotatably mounted on a shaft and carry the three pulleys and core spindles. A friction adjuster is provided, having a pulley adapted to contact with the belt and means for moving the pulley and securing it in adjusted position, whereby it 30 deflects the belt sufficiently to have a proper frictional engagement with one of the core spindle pulleys.

25 The core spindles have a squared end adapted to be received in a clutch rigid with one of the core pulleys and the other end of the spindle is adapted to receive the end of a pointed member which is carried by one of the core spindle frames. The pointed member is integral with a cone and a shaft, the 40 cone contacting with a series of ball bearings suitably positioned by a cup contacting with the wall of a cylindrical box and actuated by a helical spring to direct the center into position to support the core spindle. The 45 core spindle frames may be moved to prop-

erly position successive spindles to wind in the paper. Means are provided to act in an automatic manner on the core spindle frames and hold them in proper position for the winding operation. The rotation of a lever manually operates to release the automatic engaging means and advances the core spindle frames, when desired. 60

The primary object of the invention is the provision of a construction by which extreme delicacy of the adjustment of the winding force on the core spindle is acquired. 65

While it is old to rotate a shaft by belt friction, applicant has adapted belt drive to machines having multiple core spindles and brought the adjusting lever to the side of the machine on which the operator is stationed. 70

A feature is the arrangement of parts, 75 whereby one core may be shifted out of winding position without disturbing the mechanism for adjusting the frictional drive of the core spindle.

Ball bearings have been used on rotating shafts, but applicant's novel construction reduces friction to a very minimum. The pointed member revolves with the core spindles and the cup and cone slide in the box of the arms of the frame and are held forward with a spring. This allows the core spindles to be taken out and replaced while the ball bearing reduces the friction caused by the weight of the paper and spindles and also the end thrust of the spring. 80 85

It is apparent that the structure associated with the ball bearing and the structure associated with the pulley adapted to regulate the frictional contact of the belt with the core spindle pulley, cooperate to produce a device especially sensitive in the rewinding operation. The belt drive is adapted readily to permit slippage of contacting surfaces, so that extreme tension on the paper is not developed and the great decrease in the friction produced in the rotation of the core spindle is such that very little power is required to rotate the spindle, so that the tension on the paper being rewound may be regulated exactly by the pulley operating to 90 deflect the belt. 95 100 105

A further object of this invention is the ready and convenient manner of rotating the core spindle frames. This may be done entirely by the movement of one hand. No 110

longer is it necessary, as in the case of devices of the prior art, to unlock the frames with one hand and turn them to a proper position with the other. The use of merely one hand allows the operator to regulate the speed of the machine at the same time that he alters the position of the core spindle frame. On the advancement of the frame to a proper position, an automatic locking thereof results, so that the frame is secured properly in position, yet is readily manipulable to put another core spindle into operation.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of the present invention constructed according to the best mode I have so far devised for the practical application of the principles thereof, and in which,

Figure 1 is a side view of the entire machine.

Figure 2 is a cross section thereof on the line 2—2 of Figure 1, and

Figure 3 is a side view of the parts shown in Figure 2 taken in a direction opposite to that of Figure 1.

The machine is provided with a frame 10 for carrying the various parts of the mechanism. A large roll of paper 11 is mounted at the rear end thereof, supported on a shaft 13, rotating in bearings on arm 14, rigid with the frame 10. A support 12 is integral with arm 14 and a leg 15. The paper is unwound in a sheet 16, which is fed past feed roll 17 on to a bed roll 18, past perforating roll 19, slitters 20 and feed roll 21. The operation of perforating and slitting are described in the application above identified. The sheet 16 is then rewound upon core spindle 22. Core 22 is similar to cores 22' and 22''. They have squared ends 23, adapted to be received in a clutch 24, rigid with shaft 25 which is rotatable by pulley 26.

The shaft 25 rotates on ball bearings 27, carried in cylinders 28 on the ends of arms 29 of core spindle frame 30, rigid with frame shaft 31, which is rigid with a similar frame 32, having arms 29' thereon, terminating in cylindrical boxes 33. The boxes house a center 34, adapted to be received in the end of the core spindle and integral with a shaft 35 and a cone 36. The cone bears against ball bearings 37 in cup 38, urged inwardly by spring 39. The extreme

inward movement of the pointed member 34 is limited by collar 40 on shaft 35. On the rotation of pulley 26, clutch 24 is rotated, as is also the core spindle. The spindle may be removed from clutch 24 by withdrawing center 34 slightly.

The ball bearing structure minimizes the friction produced in moving pulley 26, the structure associated with the center contributing to this effect, as the cup and cone are slideable in the box and held forward by the spring. The ball bearings reducing the friction caused by the weight of the paper and the spindles and also the end thrust of the spring.

Pulley 26 is rotated by belt 41, running on pulley 42, adjustable by nut 43 in slot 44, on frame 10. From pulley 42 the belt extends downwardly to pulley 45, then upwardly to pulley 46. In order to adjust the frictional action of the upper stretch of belt 41 on core spindle pulley 26, an adjuster is provided. It consists of a sheave 47, rotatable on a pivot 48 running thru the end of arm 49, which has limited rotatory movement on pivot 50, carried in a support 51, integral with an upper extension 52 of the frame. To the end of pivot 48, link 53 is secured by nut 54 and its lowermost end has pin 55 extending thru it and crank 56, rigid with shaft 57, from which arm 58 extends upwardly adjacent side frame 10', having slot 59 therein, arm 58 being secured in proper adjustment by bolt 60 on which wing nut 61 is rotated, bolt 60 extending thru slot 59.

The operator, by moving arm 58 to either side, alters the elevation of sheave 47 and regulates the degree of depression thereof upon belt 41. A greater depression of the belt results in a greater amount of drive, thereby on pulley 26 and produces a greater tensioning action on the paper being rewound on the core spindle. The minimizing of friction in the rotating of the spindle permits a nicety of adjustment between the frictional drive upon pulley 26 and the tensioning of the paper on the core spindle, so that danger of breaking the very fragile stretches of paper is eliminated.

A proper tension is maintained on belt 41 by pulley 46 which is urged upwardly by lever 62 rotating on pivot 63, secured to side 10. Spring 64 has one end secured to the side frame at 65 and the other at 66 to lever 62, and the tension of spring 64 is transmitted thru pulley 46 to belt 41. Power is applied to pulley 45 thru shaft 67 running thru leg 68 of the frame and rigid with sheave 69, on which moves belt 70, running to dead roll pulley 71, shown in dotted lines in Figure 1.

As explained in the above identified patent, power is transmitted originally to shaft 72, rigid with bed roll 18 and pulley 71 is thus rotated. Gear 73, rigid with shaft

72 operates thru gear 74 to rotate slitters 20, and gear 74 operates thru gear 75 to rotate perforating roll 19.

When the core spindle has been so rotated 5 that the roll rewound thereon has attained a desired diameter, an attendant lifts up on handle 76, on lever 77, rotatable on shaft 31 and causes pawl 78, secured to lever 77 by pin 79, to engage with shoulder 80 on disc 81, rigid with shaft 31, to move forwardly. Shoulders 80—80' and 80'' are spaced equal distances circumferentially on disc 81.

Simultaneously with the upward movement of handle 76, dog 82 moves downwardly and contacts with cam 83 of arm 84 extending thru side wall 10' and rigid with arm 85, and catch 86, to move catch 86 downwardly and disengage it from a lug 87. Lugs 87 are three in number and rigid with cylindrical boxes 33. The downward movement of catch 86 releases the lug and permits pawl 78, which then engages with shoulder 80, to rotate the gear spindle frame, 20 thus positioning another spindle in position for rewinding.

As the spindle is moved into proper position for rewinding, another lug 87 wipes past an arm of bell crank 88, the upper limit 30 of movement of said arm being determined by stop 89, contacting therewith, the stop being rigid with side frame 10. Bell crank 88 is urged upwardly normally, as is also catch 86, by reason of the tension of spring 35 90, secured to eyes 91 and 92. When dog 82 wipes past cam 83 at the lowermost point of movement of the cam, the cam is then freed to return to its uppermost position, which is determined by stop 93. Catch 86 40 being rigid with cam 83 is also restored to its normal uppermost position, in which it is operative to engage cam 87, which wipes past the arm of bell crank 88.

It will be noted that the rotation of the 45 core spindle frames is clockwise, as viewed in Figure 1, and the upward movement of pulley 26 necessitates a deflection of belt 41 thereabove. This movement is permitted by the compensating action of pulley 46, 50 which moves downward against the tension of spring 30. When the next succeeding pulley 36 is properly positioned, pulley 46 is restored to the position shown in Figure 1.

1. The advancement of the core spindle 55 frame and the securing thereof in proper position is therefore accomplished by the movement merely of one hand actuating handle 76. The lowermost core spindle, namely core spindle 22'', contacts with rolls 93 on shaft 94, rotatable in paste trough 95. This provides a convenient means for applying paste to the core spindle. Wheel 96 is provided rigid with shaft 94 for rotating rolls 93.

60 65 When a core spindle is swung upwardly

from the trough, it has had the necessary paste applied to it by pasting rolls 93. After the newly pasted core comes in contact with the paper bands, the machine may be stopped and the paper between the completed rolls and newly pasted cores may be torn by hand. The paper is then wound on the newly supplied core. 70

As is apparent from a consideration of Figure 3, wheel 96, handle 76, and arm 58, 75 75 are within convenient reach, the lowermost limit of position of lever 77 being determined by stop 97.

I claim:

1. The combination of a plurality of pulleys, a belt running over said pulleys, a plurality of core spindle pulleys, means carrying said last named pulleys, means supporting said first named pulleys, and adjusting means cooperating with said belt for deflecting said belt to a greater or lesser extent to engage one of said core spindle pulleys. 80 85

2. The combination of a frame, a plurality of pulleys carried thereby, a belt running over said pulleys, a plurality of core 90 spindle pulleys, means carrying said last named pulleys, an adjustor pulley, means for altering the position of said adjustor pulley whereby it deflects said belt to a greater or less degree to exert a greater or 95 less frictional drive on one of said core spindle pulleys.

3. The combination of a frame, a plurality of pulleys carried thereby, triangularly positioned, a belt running over one of said 100 pulleys, a plurality of core spindle pulleys, means carrying said last named pulleys operable to position one of said last named pulleys, adjacent a stretch of said belt, an adjustor pulley, and means for altering the 105 position of said adjustor pulley to produce a greater or lesser frictional drive of said belt on one of said core spindle pulleys.

4. The combination of a frame, a plurality of pulleys carried thereby, a belt running over one of said pulleys, a plurality of core spindle pulleys, an adjusting pulley 110 contacting with said belt and operable to deflect said belt against one of said core spindle pulleys, means for varying the adjustment of said adjusting pulley, and means for securing said pulley in adjusted position. 115

5. The combination of a frame, a plurality of pulleys carried thereby, a belt running over said pulleys, a plurality of core spindle pulleys, an adjusting pulley, a pivot for said adjusting pulley, an arm carrying said adjusting pulley, said arm being pivoted to said frame, a link secured to said 120 pivot, and means for varying the position of said link to vary the position of said pulley, whereby a greater or lesser frictional drive is exerted upon one of said core spindle 125 pulleys. 130

6. The combination of a frame, a plurality of pulleys carried thereby, a belt running over said pulleys, a plurality of core spindle pulleys, means carrying said last named pulleys, an adjusting pulley, means securing said pulley for revolution about a point on said frame, a link, an arm pivoted to said link, means secured to said arm and running transversely thru said frame for securing said arm, said link and said pulley in diverse positions, whereby said pulley cooperates with said belt for exerting a greater or lesser frictional drive upon one of said core spindle pulleys. 45
- 10 7. The combination of a frame, a plurality of pulleys carried thereby, a belt running over said pulleys, a plurality of core spindles, means supporting said spindles for rotation, a plurality of core spindle pulleys cooperating with said spindles to rotate said spindles, and adjusting means for varying the frictional drive of said belt upon one of said core spindle pulleys. 50
- 15 8. The combination of a plurality of pulleys, means supporting said pulleys, a belt running over said pulleys, a plurality of core spindles, means carrying said core spindles and supporting said core spindles for rotation, a plurality of core spindle pulleys 55
- 20 carried by said means cooperating to rotate said core spindles, a manually operable lever, automatic means actuatable by said manually operable lever to vary the position of said core spindles, and secure said core spindles in diverse positions, and means for varying the frictional drive of said belt upon one of said core spindle pulleys. 60
- 25 9. The combination of a plurality of pulleys, means supporting said pulleys, a belt running over said pulleys, a core spindle, a plurality of ball bearings, means cooperating with said ball bearings and said core 65
- 30 40 spindle for supporting said core spindles for rotation, a core spindle pulley and means for varying the frictional drive of said belt upon said core spindle pulley. 70
- 10 11. The combination of a plurality of spindles, a pair of frames supporting said spindles for rotation, a shaft carrying said frames, means supporting said shaft for rotation, a ratchet disc on said shaft, a manually operable lever rotatably mounted on said shaft, a pawl on said lever adapted to operate said disc on the movement of said lever in one direction to rotate said disc, a plurality of lugs on one of said frames, means permitting passage of said lugs in one direction on the rotation of said shaft by 75
- 35 said lever and operative to prevent reverse movement of said lugs, means cooperating with said lugs to prevent further advancement thereof, a dog carried by said lever, and means cooperating with said dog and operative upon movement of said lever to release said last mentioned means, whereby said shaft may be further rotated. 80
- 40 In testimony that I claim the foregoing I have hereunto set my hand at Green Bay, in the county of Brown and State of Wisconsin.

LOUIS A. STRAUBEL.
